UNITED STATES PATENT OFFICE.

JOSEPH B. STRAUSS, OF CHICAGO, ILLINOIS.

BRIDGE.

1,111,872.

Specification of Letters Patent. Patented Sept. 29, 1914.

Application filed July 6, 1909. Serial No. 505,989.

To all whom it may concern:

Be it known that I, JOSEPH B. STRAUSS, a citizen of the United States, residing at Chicago, in the county of Cook and State of Illinois, have invented a certain new and useful Improvement in Bridges, of which the following is a specification.

This invention relates to improvements in bridges, and has for its object to provide a new and improved bridge of the lift bridge type.

The invention is illustrated in the accompanying drawings, wherein—

Figure 1 is a view of one form of bridge embodying the invention; Fig. 2 is a sectional view through the counterweight and bridge racks and the guide therefor; Fig. 3 is a view in part section showing the top of one of the bridge supports and the well 20 into which the racks project; Fig. 4 is a view showing a modified construction; Fig. 5 is a diagrammatic view showing a construction where the bridge span can be used in connection with two roadways, one above the other; Fig. 6 is a sectional view taken on line 6—6 of Fig. 1.

Like numerals refer to like parts throughout the several figures.

Referring now to the drawings, there is illustrated a bridge span 1, adapted to be lifted bodily and provided at each end with the supports or towers 2, 3. Connected with each end of the bridge span are the racks 4 which engage pinions 5. Counterweights 6 are mounted so as to move along the towers 2 and 3, and are connected with racks 7 which also engage pinions 5. These counterweights are, as it were, concentrated at the ends of said racks. The racks 4 are preferably movably connected with the bridge span so as to permit expansion and contraction thereof, there being preferably two or more racks at each end of the bridge span. As shown in Fig. 1, the rack 4 is connected to the bridge span by a link 8 which is pivotally connected with the rack and with the bridge span. The racks 4 and 7 are preferably guided so as to run freely up and down and prevent binding. One arrangement for this purpose is shown in detail in Fig. 2. In this construction the guide post or frame piece 9 is provided on each side with one or more projecting parts 10, carrying a series of rollers 11 and 12, there being laterally projecting parts 13

which carry the rollers 14 and 15. The racks 4 and 7 are provided with engaging side-pieces 16 which engage the rollers 14 and 15 and being provided with angular guiding pieces 17 which engage rollers 11 and 12. It will be noted that the guiding and supporting parts on the frame piece project into the racks, as it were, said racks being provided with a recess or groove 18 for this purpose, the rack inclosing the 65 guiding and supporting device, such guiding and supporting device and the inclosing rack arranged so that the rack is free to move longitudinally, but is fixed against lateral movement. The racks can be formed 70 in any desired manner, but are preferably formed in such a way as to be hollow, and assembled so that the guiding device projects into the hollow of the racks. It will be understood, of course, that there are 75 preferably at least two racks at each end of the bridge and two sets of guiding devices, only one set being shown in Fig. 2. This construction is shown in Fig. 6, where the two racks 7 are illustrated, the counterweight 80 extending between them and being, as it were, equally distributed between them. These towers form framed structures for supporting the counterweight and extend from truss to truss of the bridge span, there 85 being provided transmitting members comprising the racks which connect the span and the counterweight.

The main span 1 is supported upon the piers 19, said span being mounted thereon 90 so that it is free to expand and contract under variations of temperature. As shown in Figs. 1 and 3 the piers are provided with supports 20 for the bridge span. The piers are provided with openings or wells 21 to 95 receive the racks 4 and 7. It will be seen that the ends of the racks 7 descend into these wells as the bridge span is lifted. The racks are shown in this position in Fig. 3. One of the pinions 5 for the racks is shown 100 in dotted lines in Fig. 2, and is mounted upon the frame piece 9. These pinions are operated in any desired manner, and as herein shown are operated by electric motors 105 22, 23, which are connected to the pinions by any suitable power transmitting means such as the shaft 5. Some means is provided for keeping the main span in a substantially horizontal position, that is, for preventing one end from being moved up 110

faster than the other. As herein shown there is connected in the circuit of the motor 23 a variable resistance 24, controlled by a moving arm 25 pivotally connected with the bridge. The motor 22 has a variable resistance 26 in circuit therewith controlled by an arm 27 pivotally connected with the bridge. As shown the arms 25 and 27 are operated by gravity. It will be seen that if the motor 22, for example, operates at a greater speed than the motor 23 the main span will be tilted so that the arm 27 will move to cut resistance into the circuit of motor 22, and the arm 25 will then move to cut resistance out of the circuit of motor 23, thus tending to slow down motor 22 and speed up motor 23 and cause the bridge to be brought to a horizontal position. If motor 23 operates more rapidly than motor 22, so as to lift the right end of the bridge higher than the left end, the inclination produced will cause the arms 25 and 27 to move in the opposite direction so as to automatically bring the bridge span to its proper position. It will thus be seen that the bridge span is provided with a controlling device located on the span for controlling the operating machinery to maintain a proper alinement of the span as it rises and falls.

As shown in Fig. 4, the end of the bridge span and tower are supported upon the pier, by means of rollers 28 so as to be free to expand on account of variations in temperature. In this construction the tower and the main span are connected together through the medium of the rack and pinions and both are free to expand. The counterweight may also be separated, a portion placed at each end of the racks. This construction also permits the racks 4 to be braced by the braces 29.

In Fig. 5 there is shown a construction where there may be provided two roadways 30 and 31, one above the other, the top of the main span acting as a part of the roadway 31, and the floor thereof acting as a part of the roadway 30, so that trains or other vehicles may be passed through the towers and across the bridge at different levels to adapt the bridge to changes in the height of track. This construction might be utilized, for example, where the bridge was first formed with the track at one level, and it then became necessary to elevate the track. In such case the bridge could be lifted to the level of the elevated position of the track and let this position to be its normal position after such elevation.

I claim:

1. A lift bridge comprising two separated piers a span extending across the space between said piers and carrying a roadway and adapted to be lifted and lowered, a counterweight located above said span, and

rigid connecting pieces by means of which the counterweight and span are movably connected together.

2. In a lift bridge, a span adapted to be lifted, counterweight for said span, rigid connecting pieces by means of which the counterweights and span are connected together, a common support for the span and counterweight, and an adjustable connection between the span and the support permitting expansion. 75

3. In a lift bridge, a span adapted to be lifted, counterweight towers at the ends, rigid connecting pieces by means of which the counterweights and span are connected together, and a free connection between the span and the towers to permit change in alinement without interfering with the movement of the span. 80

4. In a lift bridge, a span adapted to be lifted, counterweight devices at the ends of said span, a link at one end of the span said link connected to one of the counterweight devices. 85

5. In a lift bridge, two frames traveling in a tower and operatively connected together, a counterweight connected to one frame and a bridge span freely connected to the other frame so as to be capable of moving independently of the frame. 90

6. In a lift bridge, two frames traveling in a tower, a pinion connecting them about which they are balanced, a counterweight connected to one frame, and a bridge span freely connected to the other frame so as to be capable of moving independently of the frame. 95

7. In a lift bridge, a span adapted to be lifted provided with separated trusses one at each side thereof, a counterweight therefor adapted to be lowered, a balancing connection between the two under compression from the counter-weight, the counterweight extending across the space between the trusses. 105

8. In a lift bridge, a span adapted to be lifted, a counterweight to balance the span, a framed structure supporting the counterweight and extending from truss to truss of the main span, transmitting members connecting the span and the counterweight and means for distributing the counterweight equally on the transmitting members. 110

9. A lift bridge comprising a vertically moving span, a vertically moving counterweight therefor, racks connected with the span and counterweight, a pinion connecting the two racks, a supporting pier upon which the pinion is carried, and a well within said pier to receive the racks as they are lowered. 120

10. A lift bridge comprising a pier, a tower supported thereon, a counterweight, a bridge span, the said span and counterweight movably mounted upon the tower so 130

as to be free to move in opposite directions, a rigid connection between the counterweight and span operatively connecting them together, and a seat upon the pier for the bridge span.

11. A lift bridge comprising two separated piers, a vertically moving span extending across the space between said piers and carrying a roadway and a rack at each end 10 of said span, a counterweight at each end of said span, pinions connecting the racks of the counterweight with the racks of the span.

12. A bridge comprising a vertically moving span, a vertically moving counterweight, rigid connection between them, a guiding device therefor, the span and counterweight on opposite sides of said guiding device.

13. A bridge comprising a vertically mov-

ing span, a vertically moving counterweight, 20 a central guide post, racks on opposite sides of said guide post, one connected to the counterweight and the other to the moving span, a series of rollers connected with said guide post and engaging said racks, and restraining them against displacement.

14. A bridge comprising a moving span, a rack connected therewith, a counterweight, a rack connected therewith, a guiding device projecting into said racks, and a connection between the two racks.

Signed at Chicago, Illinois, this 17th day of June, A. D. 1909.

JOSEPH B. STRAUSS.
